Primary Examiner — Karen Kearney*Assistant Examiner* — Katherine Holbrow(74) *Attorney, Agent, or Firm* — Lerner, David, Littenberg, Krumholz & Mentlik, LLP**CLAIM**

The ornamental design for a display screen with graphical user interface or portion thereof, as shown and described.

DESCRIPTION

FIG. 1 is a front view of a first image in a sequence for a display screen with graphical user interface or portion thereof, according to a first embodiment;

FIG. 2 is a front view of a second image thereof;

FIG. 3 is a front view of a third image thereof; and

FIG. 4 is a front view of a fourth image thereof.

FIG. 5 is a front view of a first image in a sequence for a display screen with graphical user interface or portion thereof, according to a second embodiment;

FIG. 6 is a front view of a second image thereof;

FIG. 7 is a front view of a third image thereof; and,

FIG. 8 is a front view of a fourth image thereof.

The appearance of the transitional image sequentially transitions between the images shown in FIGS. 1-4 and 5-8. The process or period in which one image transitions to another image forms no part of the claimed design.

The broken line showings of the display screen, text and other features are included for the purpose of illustrating portions of the article and form no part of the claimed design.
